CLAIM

The ornamental design for a playback device, as shown and described.

DESCRIPTION

FIG. 1 is a front view of a playback device, according to a first embodiment of our new design;

FIG. 2 is a rear view thereof;

FIG. 3 is a top view thereof;

FIG. 4 is a bottom view thereof;

FIG. 5 is a left view thereof;

FIG. 6 is a right view thereof;

FIG. 7 is a perspective view thereof; and,

FIG. 8 is another perspective view thereof.

The broken lines, including broken line surface shading, illustrate portions of the article that form no part of the claimed design. The dot-dash-dot broken lines illustrate a boundary and form no part of the claimed design.

1 Claim, 8 Drawing Sheets**Related U.S. Application Data**

a continuation of application No. 29/577,674, filed on Sep. 14, 2016, now Pat. No. Des. 806,678, which is a continuation of application No. 29/525,027, filed on Apr. 25, 2015, now Pat. No. Des. 768,602.
